UNITED STATES PATENT OFFICE

SAMUEL A. SCHWARTZ, OF ST. PAUL, MINNESOTA

CABINET FOR TOWELS

Application filed November 12, 1931. Serial No. 574,494.

This invention relates to towel cabinets. It is the general object of this invention to provide a novel and improved cabinet adapted for efficient use in lavatories and the like and wherein a clean towel roll may be held adjacent the top of the cabinet.

To this end, generally stated, the invention consists in the novel parts and novel combinations of parts hereinafter defined in the claims and described in the following specification, made in connection with the accompanying drawings, wherein like reference characters refer to the same or similar parts throughout the various views and in which,

Fig. 1 is a vertical section taken from front to rear through a towel cabinet embodying the invention with toweling in place therein, the section being taken on the line 1—1 of Fig. 2;

Fig. 2 is a view in front elevation of the cabinet with the door opened, only a portion of the door being shown and the toweling being removed from the cabinet;

Fig. 3 is a view in outer side elevation of one of the side frames of the cabinet;

Fig. 4 is a view in outer side elevation of a portion of the other of the side frames;

Fig. 5 is a detailed view in outer side elevation of the mechanism for controlling the delivery of toweling from the cabinet, a portion of the door of the cabinet being shown in vertical section;

Fig. 6 is a similar view showing this same mechanism in a different position;

Fig. 7 is a view in inner side elevation of the bolt forming a part of the said mechanism; and

Fig. 8 is a view in inner end elevation of this same bolt.

In accordance with the invention, there is provided a casing 9 of rectangular shape and having an open front normally closed by a door 10 mounted on hinges 10a secured to the forward edge of one side of the casing. The casing 9 has solid sides, top and back and it is partly closed at its bottom by means of a slat 11, the forward edge of which is spaced rearwardly somewhat from the front of the casing to provide a passage 12 between the

forward edge of the slat and the door 10 when the door is closed. The rear edge of the slat 11 is spaced forwardly some distance from the back of the casing to form quite a large opening 13 in the bottom of the casing. The door 10 may be equipped with a mirror 14, as is usual in towel cabinets, and eyes 15 may be secured to the upper portion of the back of the casing to permit the cabinet to be hung on a wall or the like. A pair of side frames 16 and 17 respectively, are provided and these side frames are generally of similar formation with the exception that one of the side frames, as the side frame 16, is adapted for use at the right side of the casing and the other of the side frames 17 is adapted for use at the left side of the casing. Each side frame extends from the bottom of the casing to adjacent the top thereof and the side frame 16 fits against and is secured to the right side of the casing, while the other side frame 17 fits against and is secured to the other side of the casing. Both side frames have outwardly flanges at the four edges thereof and their body portions are therefore spaced inwardly somewhat from the sides of the casing.

A U-shaped trough 18 has vertical arms which are disposed adjacent the respective side frames 16 and 17, but which have no connection therewith, and these arms have in-turned flanges at their upper ends by which the trough is attached to the top of the casing 9. The bottom of the trough is located in spaced relation from the top of the casing 9 and it has a forward upwardly rolled edge which extends approximately flush with the front of the casing. The rear portion of the bottom of the trough 18 is upwardly curved as best shown in Fig. 1 to extend over the upper forward quadrant of a clean towel feed roller 19 having trunnions journaled in the two side frames 16 and 17 slightly behind the bottom of the trough 18. A clean towel roll 20 of toweling A is adapted to be held within the trough 18 and from this clean towel roll the toweling extends rearwardly over the rear portion of the bottom of trough 18, thence rearwardly over the feed roller 19 and forwardly to the front of the casing 9 over the

top of a small alining roller 21 having trunnions journaled in the side frames 16 and 17 adjacent the forward edges thereof and slightly below the forward edge of the bottom 5 of the trough 18. Slidably mounted on the slat 11 between the two side frames 16 and 17 is a plate 22 having a downwardly rolled forward edge normally fitting within the passage 12 and an upwardly rolled rear edge or 10 interlocking portion 23 normally disposed adjacent the back of casing 9. The interlocking portion 23 cooperates with a pair of vertically spaced rods 24 loosely mounted in the side frames 16 and 17 adjacent the rear 15 corners thereof. The two rods 24 form in effect a cooperating interlocking member for the interlocking portion 23. When the door 10 is open, the forward edge of the plate 22 may be grasped and the plate may be slid 20 forwardly from the full line position illustrated in Fig. 1, to the dotted line position there shown, whereupon the rear part of the plate will be withdrawn from above the opening 13. To retain the plate 22 in rearwardly 25 slid position when the door 10 is closed, with the interlocking portion 23 urged into engagement with the rods 24, a pair of rubber pins 25 are used and these pins are applied to the inner side of the door 10 adjacent the 30 edges thereof for engagement with the forward edge of the plate 22. The toweling A runs downwardly from the alining roller 21 through the passage 12 forward of the forward edge of the plate 22 and depends downwardly below the cabinet in a loop. The rear run of the loop of toweling A extends 35 upwardly through the opening 13 between the interlocking portion 23 and the rods 24.

The trunnions of a soiled towel feed roller 40 26 are journaled in the side frames 16 and 17 adjacent the lower ends thereof and midway between the front and rear edges thereof. A slot 27 is cut in the side frame 17 above the feed roller 26 and this slot is cut radially relative to the rotating axis of the roller 26 and it extends upwardly and somewhat rearwardly from the roller. An angular slot 28 is cut in the side frame 16 and the lower portion of this slot faces and is directly opposed from the slot 27, while the upper portion of the slot 28 runs forwardly through the forward edge of the side frame 16. The trunnions of a removable soiled towel take-up roller 29 are journaled within the two slots 27 and 28 and 50 this roller together with whatever toweling may be wound thereon rests by gravity against the soiled towel feed roller 26. As will be noted from an inspection of Fig. 1, the roller 29 together with whatever toweling A may be wound thereon, engages the roller 26 slightly rearwardly and slightly below the extreme top portion of the roller 26. The toweling A after passing between the interlocking portion 23 and the rods 24 runs upwardly to the roller 29 and is wound thereon.

60

65

It should perhaps be here stated that the two feed rollers 26 and 19 are covered with sand paper or other friction material.

Mounted on the left trunnion of the two feed rollers 19 and 26 respectively, are respective sprockets 30 and 31 and a sprocket chain 32 is trained over the two sprockets 30 and 31. The sprockets and sprocket chain are disposed between the side frame 17 and the left side of the casing 9, as viewed in the drawings.

Mounted on the right hand trunnion of the soiled towel feed roller 26, between the side frame 16 and the right side of casing 9, is a disk 34, best illustrated in Figs. 5 and 6. A pair of outwardly projecting pins 35 and 36 respectively are secured to this disk 34 and in the particular arrangement shown, the pin 35 is radially spaced closer to the center of the disk than is the pin 36 and the pin 36 is located in circumferentially spaced relation from the pin 35 a number of degrees in advance of the pin 35 relative to the normal direction of rotation of the disk 34. Secured to the side frame 16 between the side frame and the right side of casing 9, is a channel shaped guide casing 37 horizontally disposed and having an inturned flange at its forward end. A sliding bolt 38 is mounted within the channel of the guide casing 37 for sliding movement forwardly and rearwardly therein, and this bolt has a forwardly projecting pin 39 which extends through a notch in the inturned forward flange of the guide casing 37 and also through an opening in the forward flange of the side frame 16. The door 10 has an opening 40 cut therein adapted to be aligned with the pin 39 when the door is closed, and the door is recessed to enlarge opening 40 at the two sides of the door to accommodate a shouldered push button 41, the sliding movement of which is limited in one direction by the shoulder of the push button and is limited in the other direction by a screw 41a preventing the push button 41 from being completely removed from the opening 40. A coiled pressure spring 42 bears at one end against the inturned forward flange of guide casing 37 and this spring surrounds the pin 39 and is anchored at its other end to the pin. This spring, accordingly, normally urges the bolt 38 forwardly or toward the front of the casing. When the door 10 is closed, the possible forward movement of the bolt 38 is limited by engagement between the forward end of the pin 39 and the screw 41a of the push button 41. When the door 10 is opened, further forward movement of the bolt is possible, this movement being only limited by engagement of the forward end of the bolt proper with the inturned forward flange of the guide casing 37. The bolt 38 and pin 39 are of such length and are so disposed relative to the disk 34 that when the door 10 is closed, the

lower rear corner of the bolt will overlie the upper forward portion of the disk, the inner rear corner of the bolt being cut away at 38a to receive this portion of the disk. A deeper cut or channel 38b is also made in the lower rear corner of the bolt to form two shoulders 38c and 38d spaced from each other on the bolt. The channel 38b is of sufficient depth to permit the pins 35 and 36 to pass through this channel without striking the bolt 38, if the pins 35 and 36 happen to be alined with this channel as the disk 34 is rotated. The shoulders 38c and 38d are so positioned relative to the pins 35 and 36 that when the door 10 is closed and the push button 41 is forwardly extended to its extreme position, as shown in Fig. 5, the shoulder 38c will be in the path of movement of the pin 35 and the pin 36, when the pin 35 engages the shoulder 38c, will be in the path of movement of the shoulder 38d as the bolt 38 is slid rearwardly by pressing the push button 41. Assuming the parts are in the position as shown in Fig. 5, rotation of the disk 34 and of the feed rollers 26 and 28 in a clockwise direction, as viewed in Figs. 5 and 3, will be prevented by the engagement of pin 35 with shoulder 38c. As the push button 41 is pressed inwardly, the shoulder 38d will strike the pin 36 and thereby rotate the disk 34 for a short distance. The channel 38b is so placed relative to the pin 35, that as this occurs the shoulder 38c will be carried rearwardly beyond the pin 35 and the pin 35 will be swung to the position shown in Fig. 6 within the channel 38b. Of course, shortly after the parts have taken the position shown in Fig. 6, the spring 42 upon release of the push button 41, will move the bolt 38 back to its original position as shown in Fig. 5, but the pin 35 will no longer engage the shoulder 38c and as a result, it will be possible to rotate the disk 34 through nearly a complete revolution, or until the pin 35 again strikes the lower side of the shoulder 38c. During this latter movement, the pin 36 will freely pass through the channel 38b of the bolt, to again assume its original position as shown in Fig. 5. If the door 10 should be opened, the spring 42 will immediately move the bolt 38 forwardly to such a position that the lower rear corner of the bolt will not overlie the disk 34 and as a result, it will be perfectly possible to rotate the disk without interference by the bolt 38 when the door 10 is open.

To fill the cabinet and set it up ready for use, the door 10 will be first opened, whereupon the plate 22 will be grasped and slid forwardly. A roll 20 of clean toweling A may then be deposited within the trough 18 whereupon the free end of the toweling A will be grasped and carried rearwardly over the clean toweling feed roller 19 and thence forwardly and over the top of the alining

roller 21. As, when the door 10 is open, the bolt 38 is projected forwardly beyond the disk 34, it is possible to freely rotate both feed rollers 19 and 26 and the roller 19, accordingly, will not prevent the toweling being payed out from the clean toweling roll 20. After the toweling A has been carried over the roller 21, the free edge of the toweling will be carried downwardly in front of the forward edge of the plate 22 and sufficient toweling will be drawn out to form a loop of toweling of the desired length below the casing. The free edge of the toweling may then be pushed up through the opening 13 between the interlocking portion 23 of plate 22 and the rods 24 whereupon several turns of the toweling will be wound on the soiled toweling take-up roller 29. If it is desired to remove the roller 29 from the cabinet to wind the toweling thereon, this may be readily done by pushing the roller 29 upwardly to its limit of upward movement in the slots 27 and 28 whereupon the right end of the roller may be swung forwardly and out of the slot 28 to withdraw the left end of the roller from the slot 27. After a quantity of the toweling has been wound on the roller 29, the roller may be as easily reinserted within the cabinet to rest by gravity against the soiled toweling feed roller 26. The plate 22 may now be slid rearwardly to the full line position, Fig. 1, and the door 10 may be shut to cause the toweling A to be engaged between the interlocking portion 23 of the plate 22 and the rods 24. The cabinet is now ready for use.

A person wishing to wipe his hands on a fresh piece of toweling, may press the push button 41, release the same and then draw downwardly on the front run of the depending loop of toweling. As the push button 41 is pressed, assuming that rotation of the feed rollers 19 and 26 has hitherto been impossible, by reason of the engagement of pin 35 with the shoulder 38c of bolt 38, the disk 34 will be given a short initial rotation by engagement of the shoulder 38b with the pin 36 as has been above explained, whereupon the disk 34 will be unlocked or released to permit the free rotation of the disk 34 and the two rollers 19 and 26 through the balance of a complete revolution as the front run of the loop of toweling A is drawn downwardly. As the movement of the toweling A occurs, the same quantity of toweling that is drawn from the clean toweling roll 21 will be wound upon the soiled toweling take-up roller 29. The interlocking portion 23 of plate 22 and the rod 24 place sufficient friction on the toweling web prior to its passage to the soiled toweling take-up roller 29 that the toweling will not overrun on the take-up roller as the operator ceases to pull the toweling. As a result, the soiled toweling will be evenly wound onto the roller 29 and it will be tightly wound

thereon. After the operator has pulled downwardly on the front run of the depending loop of toweling A for a short time, the pin 35 will be rotated to such a position that it 5 again engages the shoulder 38c, whereupon further movement of the feed rollers 19 and 26 and further dispensation of clean portions of the toweling will be prevented until the push button 41 is again pressed in- 10 wardly. There is, of course, some slight play between the trunnions of the take-up roller 29 and the portions of the side frames 16 and 17 forming the walls of the slots 27 and 28. Slight bodily movement of the roller 29 to- 15 gether with whatever toweling is wound thereon, is thus possible in a forward and rearward direction. The towel cabinet is usually made of as short a depth as possible to accommodate the particular size roll of 20 toweling for which it is intended. It is, of course, desirable that the soiled toweling wound upon the roller 29 never come in contact with the vertical run of clean toweling depending from the alining roller 21. As the 25 take-up roller 29 together with whatever soiled toweling is wound thereon, contacts the soiled towel feed roller 26 slightly below the extreme upper portion of the feed roller, it will not be possible for the soiled 30 toweling on the roller 29 to strike the clean toweling at any time even though a large quantity of soiled toweling is wound on the roller 29, and even though the play between the trunnions of the roller 29 and the por- 35 tions of the side frames 16 and 17 forming the sides of the slots 27 and 28 is sufficient to permit engagement between the soiled toweling and the clean toweling, if the roller 29 is moved to its extreme forward position. 40 The force of gravity will retain the trunnions of the roller 29 at all times in engagement with the rear walls of the slots 27 and 28 be- 45 cause of the inclination of the slot 27 and the lower portion of the slot 28 relative to the vertical.

My mechanism for controlling the delivery of toweling from the cabinet is fully disclosed in another application for patent of mine entitled "Towel cabinet" filed simul- 50 taneously with this application. By this mechanism, the two feed rollers 19 and 26 are capable of free rotation when door 10 is opened, and it is thus readily possible to withdraw toweling from the clean towel roll 55 20, without interference by the mechanism controlling the delivery of the toweling, as the cabinet is being loaded.

By the provision of the sliding plate 22, the cabinet can be very quickly loaded and 60 yet friction can be placed against the toweling prior to the time that it is carried to the take-up roller 29 to cause the toweling to be evenly wound on the take-up roller. It will also be noted that the plate 22 acts to space 65 the soiled run of the loop a long distance

from the clean run of the loop of toweling, so that contact between the clean and soiled toweling is prevented at this point. The cabinet is compact and sanitary.

It will, of course, be understood that vari- 70 ous changes may be made in the form, details, arrangement and proportions of the various parts without departing from the scope of the present invention.

75

What is claimed is:

1. A towel cabinet comprising a casing having a front opening, a door closing said opening, means adjacent the top of said casing for supporting a supply of clean toweling, said casing having a hand receiving opening at its bottom, soiled towel take up means adjacent the bottom of the casing whereby toweling may extend downwardly from said supply adjacent the front of the casing and depend below the bottom in a loop and then extend upwardly through said hand receiving opening adjacent the rear portion of the casing to said take up means, a plate of approximately the same width as the depth of said casing, said plate being 80 slidably mounted adjacent said bottom and below said soiled towel take up means for forward and rearward movement, said plate when slid rearwardly substantially closing said hand receiving opening and pressing 85 the toweling against the rear portion of the cabinet and said plate when forwardly slid permitting threading of toweling upwardly through said hand receiving opening to said take up means, said door when closed holding 90 said plate in rearwardly slid portion.

2. A towel cabinet comprising, a casing, means adjacent the top of said casing for supporting a supply of clean toweling, said casing having a bottom provided with a hand receiving opening adjacent the back thereof, soiled towel take up means adjacent the bottom of the casing, whereby the toweling may extend downwardly from said supply adjacent the front of the casing and depend be- 105

below said bottom in a loop and then extend upwardly through said hand receiving opening adjacent the rear portion of the casing to said take up means, a plate slidably mounted above said bottom for forward and rearward movement, said plate having an up- 110 wardly rolled rear edge, said plate when slid rearwardly overlying said hand receiving opening, a pair of spaced rods mounted adjacent said bottom near the back of said cas- 115 ing, the upwardly rolled rear edge of said plate adapted to press the toweling against said rods when said plate is rearwardly slid and said plate, when forwardly slid, per- 120 mitting threading of the toweling upwardly through said hand receiving opening to said take up means.

3. A towel cabinet comprising a casing, a trough mounted in said casing adjacent the top thereof, said trough having an upturned 125

130

135

forward edge terminating in spaced relation from the top of the casing and said trough also having an upturned curved rear edge, a clean towel feed roller mounted in said casing adjacent the rear edge of said trough and over the upper forward quadrant of which the rear edge of said trough extends, an aligning roller mounted below said trough at the front of said casing, soiled towel take up means mounted in spaced relation below said trough, whereby toweling may pass from the clean towel roll rearwardly over the upturned rear edge of said trough, thence around said clean towel feed roller and thence forwardly over said aligning roller and thence downwardly below said casing to extend in a loop, and the rear run of the loop may project upwardly adjacent the back of said casing to said soiled towel take up means.

In testimony whereof I affix my signature.
SAMUEL A. SCHWARTZ.
